J. W. WESTWICK, SR

FURNACE CONSTRUCTION

Filed Aug. 11, 1927

INVENTOR.

John W. Westwick, Sr.,

BY

Fig. 6. *Geo. P. Kimmel*

ATTORNEY.

UNITED STATES PATENT OFFICE.

JOHN W. WESTWICK, SR., OF GALENA, ILLINOIS.

FURNACE CONSTRUCTION.

Application filed August 11, 1927. Serial No. 212,270.

This invention relates to furnaces, more particularly to the manner of securing the sections of the front of the furnace casing in position, and has for its object to provide, in a manner as hereinafter set forth, a new, improved, and efficient means for expeditiously, conveniently and detachably securing in position the upper and lower front sections with respect to the other parts of the furnace, and further for drawing the front sections up tightly against the dome and ash pit to avoid air leakage into the inner casing.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a sectional elevation of a furnace including an upper and a lower front section and with these latter detachably secured in position in accordance with this invention.

Figure 2 is a fragmentary view in front elevation of the upper front section.

Figure 3 is a section on line 3—3 Figure 1.

Figure 4 is a fragmentary view in front elevation of the lower front section.

Figure 5 is a section on line 5—5 Figure 1.

Referring to the drawings in detail A generally indicates a furnace structure and the latter includes a radiator B, an extended dome C, a water pan D, a firebox E and an extended ash pit F provided with a door G. A cleanout door H is shown in connection with the radiator B and fuel doors I are shown in connection with the dome C. The foregoing elements are of known construction with the exception that the extended dome C, at its front is formed with an apertured upstanding lug 1 directly above the entrance thereto, that the top wall of the ash pit, in alignment with the lug 1, is formed with an apertured upstanding lug 3. The lugs 1, 3 are arranged exteriorly of

the front sections to be presently referred to and provided with openings 2, 4 respectively.

The reference character J indicates the upper front section of known construction, with the exception that between the clean out door H and the upper fuel door I the section J is formed with an opening 5.

The lower front section is indicated at K and it is of known construction, with this exception that directly above the ash pit F the section K is provided with an opening 6.

When the front sections are mounted in position, the section J is supported on and overlaps the section K, as indicated at 7. The openings 5 and 6 are disposed at the vertical median of the sections J, K. The openings 2 and 4 are arranged at the vertical median of the dome C and ash pit F. When the front sections J and K are mounted in position relative to the other castings of the furnace, the opening 5 registers with the opening 2 and the opening 6 registers with the opening 4. Extended through the registering openings 2 and 5 is a headed bolt 7 provided with a securing nut 8 on its outer end and the bolt 7, in connection with the lug 1 and nut 8 detachably secures the upper front section J in position. Extending through the registering openings 6 and 4 is a headed bolt 9 which carries on its outer end a securing nut 10, and said bolt 9, in connection with the lug 3 and nut 10 detachably secures the lower front section K in position.

When the sections are to be arranged with respect to the outer shell or casing of the furnace, the section K is first positioned over and around the ash pit, and then the section J is positioned with respect to the dome C and radiator B.

The lugged construction of the dome and ash pit, the apertured arrangement of the front sections, the headed bolts 7, 9, and nuts 8, 10, provide for expeditiously and efficiently securing the front sections in position, to tightly secure said sections to the dome and ash pit to prevent air leakage, and further whereby when desired the sections can be readily removed. Therefore it is thought the many advantages of a means for securing front sections in position, in accordance with this invention can be readily understood, and although the preferred embodiment of the invention is as illustrated

and described, yet it is to be understood that changes in the details of construction can be had which will fall within the scope of the invention as claimed.

5. What I claim is:

1. In a furnace of that type including an extended dome and an extended ash-pit, an upper and a lower front section for the furnace casing, said upper and lower front sections seating respectively on the extended dome and ash-pit, an apertured lug integral with the top of and positioned outwardly of the front to the extended dome and further arranged to oppose the outer face of said upper section, an apertured lug integral with the top of and positioned inwardly of the front of said ash-pit and arranged to oppose the outer face of said lower section, and means extended through and connected to said lugs and adapted to extend through said sections for detachably securing them in position.

2. In a furnace of that type including an extended dome and an extended ash-pit, a front upper section for the casing of a furnace, said section seating on said dome, an apertured lug integral with the top of and positioned inwardly of the front of said dome and arranged to oppose the outer face of said section, and means extended through and connected to the lug and adapted to

extend through said sections for detachably securing them in position.

3. In a furnace of that type including an extended ash-pit, a lower front section for the casing of the furnace, said section seated on said ash-pit, an apertured lug integral with the top of and positioned inwardly of the front of said ash-pit and positioned to oppose the outer face of said section, and means extending through and connected to said lug and further adapted to extend through said section for detachably securing it in position.

4. In a furnace of that type including an extended dome and an extended ash-pit, the combination of a casing having its front formed of an upper and a lower section seating respectively on said dome and ash-pit, each of said sections having an opening near its bottom, a lug integral upon the top of the extended portion of the dome at the outer end thereof, a lug integral with the top of the extended ash-pit at the outer end thereof, said lugs opposing the outer faces of said sections, and means engaging with the lugs and extending through said openings for detachably securing said sections in position.

In testimony whereof, I affix my signature hereto.

JOHN W. WESTWICK SR.
